UNITED STATES PATENT OFFICE.

CHARLES GOODWIN, OF EAST PROVIDENCE, RHODE ISLAND.

APPARATUS FOR RAISING THE TEMPERATURE OF ARTICLES.

1,121,723.

Specification of Letters Patent. Patented Dec. 22, 1914.

Application filed January 20, 1914. Serial No. 812,158.

To all whom it may concern:

Be it known that I, CHARLES GOODWIN, a citizen of the United States, residing at East Providence, in the county of Providence and State of Rhode Island, have invented certain new and useful Improvements in Apparatus for Raising the Temperature of Articles, of which the following is a specification.

10 My invention relates to an apparatus for raising the temperature of articles.

It has heretofore been customary in gas, electric, and other furnaces, to subject the muffler or housing containing the articles to be tempered, soldered, hardened, or annealed, or otherwise heated, directly to a source or sources of heat, for which reason the heat in the muffler has not been uniform at all points; has been dissipated; and has not been retained for any substantial length of time.

15 In furnaces as at present constructed there occurs oxidation and the development of scales upon the articles being treated in the furnace, because of the presence of air. In muffler furnaces this air is admitted with the gas which is mixed therewith. Electric and coal furnaces are open to the atmosphere.

20 The essential objects of my invention are to remedy all the above enumerated defects, conserve and retain the heat in the muffler, maintain a uniform temperature in every part of the same, and to provide an apparatus that is simple and certain in operation, and inexpensive to construct.

25 To the above indicated ends my invention consists in such parts and combinations of parts as fall within the scope of the appended claims.

30 In the accompanying drawings which form a part of this specification, and in which like reference characters indicate like parts throughout the views, Figures 1 and 2 are front and side elevations respectively of my novel apparatus in conjunction with which my novel process is in the present instance performed, Figs. 3 and 4, sections of

the same on lines *a* *a* of Fig. 2 and *y* *y* of Fig. 1 respectively, and Fig. 5, a diagrammatic view of the gas piping.

35 In carrying out my process I inclose the articles to be heated in a closed chamber surrounded by a fusible metal or salts in a fused state, and apply heat to sustain the metal or salts in a fused state. In actual practice lead is found the best of the fusible metals for my purpose; and potash nitrate combined with soda nitrate the best fusible salts.

40 The novel furnace adapted to use in conjunction with the process consists of a casing or housing A comprising in the present instance a metallic shell *a* and a lining *b* of fire brick or clay. The casing is preferably U-shaped transversely, comprising a rounded base portion *a'*, vertical side walls *a*², and end walls *a*³. The top wall *a*⁴, of the casing constitutes a removable arched cover resting upon the wall portions *a*³, and is 45 provided with a vent opening *d* near one end extending into a vent pipe D fixed to the cover portion *a'*. The end walls *a*³ of the casing are provided with openings E. A metal receptacle F is provided, corresponding in general shape with the casing, but of less dimensions, and open at its top. This member is arranged concentrically of the casing and comprises a transversely rounded bottom portion *f*, upright side 50 walls *f'*, and end walls *f*². Extending longitudinally of the receptacle is a chamber G formed by a hollow or tubular housing H comprising a bottom wall *h*, side walls *h*', and a top wall *h*²; all are cast integral with 55 the end walls of the receptacle, which at their central portions are open as at *i*. The tubular housing H is continued at each end by hollow or tubular extensions J cast integral with the end walls of the receptacle, 60 and protruding into the openings E in the casing walls, whereby the entire member is supported. The extensions J are preferably but not essentially of somewhat greater 65 diameter than the central portion H whereby are formed in conjunction with the end 70

walls of the receptacle internal shoulders j , to form stops or abutments for removable plugs K of fire clay located in the extensions J . The openings E in the walls a^3 5 may, however, be closed in any manner other than by blocks if desired, as by doors.

The location of the receptacle centrally of the casing and spaced therefrom forms heating areas around all parts of the former, including a transversely curved space L at the bottom, vertical spaces l at the sides, spaces l' at the ends, and l^2 , at the top.

Heat may be supplied by any means 15 preferred. In the present instance it is furnished by gas, and is supplied by an air supply pipe N and a gas supply pipe M converging in a mixing chamber n . From chamber n extend branch pipes O and O' 20 exterior of and parallel with the sides of the casing, having respectively two inwardly directed branch pipes P and P' , terminating in burners Q and Q' respectively, disposed horizontally in opposite directions, 25 and extending through openings q and q' respectively in the lower portion of the casing into the space L . Upon the pipes P and P' respectively are bearing plates R and R' respectively contacting with the 30 exterior of the casing. It has been found advantageous, but not essential, as shown in Fig. 5 to have the burners Q and Q' disposed diagonally rather than directly opposite each other.

35 The arrows in Figs. 3 and 4 show the course of the heat from the flames of the burners, around the bottom, top, sides, and ends of the receptacle. The heat passing through the spaces l' around the extensions J communicates itself to the plugs K so as to supply heat also at both ends of the chamber G . The wall a^3 is provided with an opening S , closable by a plug s , to give access to the burners. The receptacle F is 40 filled with a fusible metal, or a combination of fusible salts, T , preferably lead, which metal or salt will be fused by the heat when the heat is applied as described. The fused salts are advantageous for producing temperatures from 300 to 600 degrees, while lead produces temperatures to 1800 degrees Fahrenheit and higher.

In operation one of the plugs K is manually removed, and the article to be tempered, soldered, or otherwise treated is placed in the chamber G , where its temperature is raised uniformly in every part, even at its top, because of the uniformity of the degree of heat in every part of the chamber, 45 due particularly to the presence around four sides of the chamber throughout its length of the fused mass T throughout which the heat is uniform. This mass also retains its heat without dissipation for a long while 50 after the flame is shut off. It will be further

observed that the air is not accessible to the chamber G so that oxidization and flaking of the article can not occur.

It is obvious that many changes in details of construction within the spirit of my invention may be made.

The description of the apparatus has been given in detail merely for clearness of understanding, and no undue limitation should be understood therefrom, for obvious modifications will occur to a person skilled in the art.

What I claim is,—

1. In an apparatus for raising the temperature of articles, the combination of a casing, a receptacle in said casing and spaced therefrom, a housing in said receptacle provided with portions extending through the casing, said receptacle adapted to receive fusible material surrounding the housing and a removable closure for an end of the housing.

2. In an apparatus for raising the temperature of articles, the combination of a casing, a receptacle in said casing and spaced therefrom, a housing in said receptacle provided with portions extending through the casing, said receptacle adapted to receive fusible material surrounding the housing, a removable closure for an end of the housing, and oppositely disposed heating means in the casing beneath said receptacle.

3. In an apparatus for raising the temperature of articles, the combination of a casing comprising a bottom, vertical side walls, end walls, and a cover, said end walls being provided with openings, a receptacle in the casing and spaced therefrom, a housing extending transversely of the receptacle provided with open end portions extending into said openings and forming supports for the receptacle, closure members for the extending portions of the housing, and burners in the casing below the receptacle.

4. In an apparatus for raising the temperature of articles, the combination of a receptacle, a housing traversing the receptacle and provided with extended open end portions, a casing surrounding the receptacle and provided with openings to receive the end portions of the housing, means for closing the end portions, and burners in the casing adjacent the receptacle.

5. In an apparatus for raising the temperature of articles, the combination of a receptacle provided with a curved bottom portion and with an open top, a casing surrounding the receptacle having openings in its sides and provided with a curved portion adjacent the curved portion of the receptacle, said receptacle and casing being spaced from each other at all points, oppositely disposed burners in the curved portion of the casing, and a housing in the receptacle extending into the openings in the casing.

6. In an apparatus for raising the temperature of articles, the combination of a receptacle, a housing extending transversely through the casing and provided with open projecting end portions, shoulders in the housing near the open ends, plugs in the end portions abutting against the shoulders, a casing surrounding the receptacle provided with openings to receive the end portions,

and burners in the casing below the receptacle. 10

In testimony whereof I have affixed my signature in presence of two witnesses.

CHARLES GOODWIN.
